UNITED STATES PATENT OFFICE.

JESSE FRAVEL, OF DAYTON, OHIO.

BARREL-CARRIER.

No. 831,424.

Specification of Letters Patent.

Patented Sept. 18, 1906.

Application filed December 13, 1905. Serial No. 291,577.

To all whom it may concern:

Be it known that I, JESSE FRAVEL, a citizen of the United States, and a resident of Dayton, in the county of Montgomery and 5 State of Ohio, have invented a new and Improved Barrel-Carrier, of which the following is a full, clear, and exact description.

The invention relates to package-carriers; and its object is to provide a new and improved barrel-carrier arranged for convenient 10 and quick attachment to one or two barrels, to enable a workman to readily carry two empty barrels with the use of but one arm and hand, and to permit two workmen to 15 carry a filled barrel with ease.

The invention consists of novel features and parts and combinations of the same, which will be more fully described herein-after and then pointed out in the claims.

20 A practical embodiment of the invention is represented in the accompanying drawings, forming a part of this specification, in which similar characters of reference indicate corresponding parts in all of the views.

25 Figure 1 is an edge view, partly in section, of the improvement arranged for one workman to carry two empty barrels. Fig. 2 is a face-view of the same, and Fig. 3 is an edge view of the improvement arranged for two 30 workmen to carry a filled barrel.

The barrel-carrier consists, essentially, of two members A and A', provided at their outer ends with sets of sidewise-extending hooks B B' and B² B³ for engaging the ends of 35 two barrels C and C' at the same time, as plainly illustrated in Figs. 1 and 2. The outer ends of the members A and A' are also provided with sets of transversely-extending hooks D D' and D² D³ for engaging the ends 40 of a single filled barrel C², it being understood that for this purpose two barrel-carriers are used, one on each side of the barrel, as plainly shown in Fig. 3. The members A and A' are also provided near their outer 45 ends with hand holds E and E', preferably in the form of longitudinally-extending bars, as shown in Fig. 2, and the inner end of the member A is provided with eyes F F', on which are secured the ends of a rope G, ex- 50 tending through eyes F² F³, formed on the inner end of the member A'. A roller-handle G' is mounted on the rope G in front of the member A', it being understood that the said rope forms an arm-support for engaging 55 with the arm of the user of the barrel-carrier, as plainly illustrated in Fig. 1.

By the arrangement described the arm-support G on account of its flexibility not only connects the inner ends of the members A and A' with each other, but serves to draw 60 the members toward each other when the device is used, so as to securely hold the corresponding sets of hooks B B' and B² B³ or D D' and D² D³ in engagement with the ends of the barrels, as above explained and shown 65 in Figs. 1, 2, and 3.

When it is desired to carry but a single filled barrel C², as shown in Fig. 3, then use is made of two barrel-carriers and the transversely-extending hooks D D' and D² D³ are 70 hooked onto the ends of the barrel, after which two workmen take hold, each with one hand, of the corresponding roller-handle G', as indicated in Fig. 3. The workmen can now readily lift the barrel C², and in doing so 75 the rope G of each barrel-carrier tends to draw the members A and A' toward each other to securely hold the hooks D D' and D² D³ in firm engagement with the ends of the barrel C². When it is desired to carry 80 two empty barrels C and C' by one workman, as shown in Figs. 1 and 2, then use is made of a single barrel-carrier and the hooks B and B² are engaged with the ends of the barrel C, while the hooks B' and B³ are engaged 85 with the ends of the other barrel C', so that the members A and A' extend between the two barrels C and C'. The operator now slips one arm through the loop formed in the rope G and then takes hold of the handhold E' 90 to lift and carry the two barrels in a very convenient manner.

It is understood that the device may be used with either of the members A or A' in top or bottom position, so that the operator 95 can take hold with the hand of either the handhold E or the handhold E'.

The barrel-carrier is preferably made of strong wire; but this is not essential, as it may be made of other material, and hence I 100 do not limit myself to the precise construction shown in the drawings.

Having thus described my invention, I claim as new and desire to secure by Letters Patent—

1. A barrel-carrier, comprising two members having hooks at their outer ends for engagement with the barrel ends, a handhold fixed on each member, and an arm-support adjustably connecting the members with 110 each other.

2. A barrel-carrier, comprising two mem-

bers provided with hooks and having hand-holds, and a flexible arm-support connecting the members with each other.

3. A barrel-carrier, comprising two members provided with hooks, and a flexible arm-support secured on one of the members and slidably engaging the other member to form an arm-loop.

4. A barrel-carrier, comprising two members, each having a set of transverse and a set of sidewise-extending hooks, and means for adjustably connecting the members with each other.

5. A barrel-carrier, comprising a pair of members having a set of transverse hooks and a set of sidewise-extending hooks, a handhold on each member, and a flexible arm-support secured at its ends to one mem-

ber and extending loosely through guideways in the other member, to form an arm-loop.

6. A barrel-carrier, comprising a pair of members having a set of transverse hooks and a set of sidewise-extending hooks, a handhold on each member, a flexible arm-support secured at its ends to one member and extending loosely through guideways in the other member, to form an arm-loop, and a roller on the said loop.

In testimony whereof I have signed my name to this specification in the presence of two subscribing witnesses.

JESSE FRAVEL.
